Attorney

UNITED STATES PATENT OFFICE

RICHARD S. WALLENBERG, OF BUFFALO, NEW YORK

FUEL ECONOMIZER

Application filed January 3, 1928. Serial No. 244,347.

The present invention relates to improvements in fuel economizers for use in conjunction with internal combustion engines.

One of the important objects of the present invention is to provide a fuel economizer wherein the same includes an auxiliary air valve unit for disposition between the carburetor and intake manifold of an internal combustion engine, a spring pressed valve being laterally released whereby additional air is admitted to the fuel as the same enters the intake manifold, the air entering the intake manifold through the valve unit being proportional with respect to the speed at which the automobile is traveling.

A further object is to provide a fuel economizer of the above mentioned character which can be readily and easily installed without necessitating any material alterations of the parts of the engine with which the device is to be associated, the economizer being further simple in construction, inexpensive, strong and durable and further well adapted to the purpose for which it is designed.

25 A further object is to provide a fuel economizer of the above mentioned character which will not only tend to decrease the fuel consumption necessary to operate the engine, but which will also tend to eliminate the accumulation of carbon and thereby increase the efficiency in the operation of the engine.

Other objects and advantages of the invention will become apparent from the following description when taken in connection with the accompanying drawing.

In the accompanying drawing wherein like reference characters indicate like parts throughout the several views:

Figure 1 is a view partly in elevation and partly in perspective of the fuel economizer embodying my invention.

Figure 2 is a top plan view of the valve unit, and

Figure 3 is a vertical sectional view therethrough, the valve being shown in its released or open position.

In the drawing wherein for the purpose of illustration is shown the preferred embodiment of my invention, the numeral 1 designates a gasket that is adapted to be disposed

between the carburetor and adjacent end of an intake manifold of an internal combustion engine, not shown. The central bore 2 of this gasket is formed with a cavity 3 in the bottom thereof as shown more clearly in Figure 1, and the purpose thereof will be hereinafter more fully described.

Also forming a salient part of the present invention is the valve unit designated generally by the numeral 4, a conical shaped body 5 that is formed at its larger end and a tool engaging portion 6, the inner face of this tool engaging portion being threaded for receiving the threaded end of the sleeve or shell 7 in the manner as clearly illustrated in Figure 3. The outer end of this shell or sleeve terminates in a tapered nipple 8 that is threaded into a suitable fitting 9 at one side thereof. This sleeve or shell is also formed with a tool engaging portion designated by the numeral 10.

The fitting 9 is in turn connected with the gasket 1 through the medium of the nipple 11, said nipple being in communication with a radial passage 12 that extends into the bore 2 as shown in Figure 1.

The body 5 is formed with a central through passage 13 and the inner end of this passage communicates with a conical shaped valve seat 14 formed in the larger end of the body. The body 5 is further formed with a series of radially disposed air passages 15 that extend from the outer face of the body into the conical seat portion 14 as is more clearly disclosed in Figure 3 of the drawing. In the present instance, three such air passages are illustrated although it is to be understood that I do not wish to limit myself to the particular number of such passages.

A tubular extension 16 is formed on the smaller end of the conical shaped body 5, and the outer end of this extension is threaded for receiving the cap 17.

A similar tubular extension 18 extends from the side of the body 5 in an upward direction and a cap 19 is threaded on the upper threaded end of this tubular extension. The body is formed with a lateral bore 20 that communicates with the tubular extension 18 while the central bore 13 of the

body communicates with the tubular extension 16 all in the manner as shown in Figure 3.

An elongated valve stem 21 extends 5 through the tubular extension 16 and through the bore 13 of the body 5, the outer end of the valve stem being slidable through a suitable opening formed in the central portion of the cap 17. A conical shaped valve 22 is carried 10 on the inner end of the valve stem for cooperation with the conical valve seat 14. A blade-like element 23 is carried on the larger free end of the conical valve 22 and is disposed within the sleeve or shell 7 as clearly 15 illustrated in Figure 3.

The valve stem 21 is formed with a detent 24 and cooperating therewith is the sliding plunger 25 that extends through the lateral bore 20 formed in the side of the conical 20 shaped body 5 and also through the tubular extension 18. The cap 19 is formed with an opening through which the upper end of this plunger extends as clearly shown in Figure 3, the lower end of the plunger is adapted to 25 cooperate with the detent 24 formed in the valve stem 21 for holding the valve stem in its outermost position whereby the conical valve 22 will be seated in the conical valve seat 14 and thereby cut off communication 30 between the air passages 15 and the sleeve 7.

For the purpose of manually controlling the plunger 25, there is provided on the instrument board of the vehicle (not shown) the plate 26, the same being formed with an 35 opening 27 through which is slidable the rod-like member 28, the same being formed at its outer end with a knob 29. A coupling 30 is secured on the upper end of the plunger 25, a similar coupling 31 being secured on the 40 inner end of the rod 28 and a cable 32 is connected at its respective end to these couplings. The intermediate portion of the cables may be trained over the guide pulley shown at 33 in Figure 1. This rod 28 is 45 formed with one or more notches such as is shown at 28^a and the purpose thereof is to provide a means whereby the rod-like member 28 may be held in any adjusted position for securing the slidable plunger 25 in a 50 raised position out of engagement with the valve stem 21 and the notch engages the bottom of the opening 27 formed in the bracket or plate 26.

A coil spring 34 is arranged within the 55 tubular extension 18 and cooperates with the plunger rod 25 for normally urging the same downwardly. A light tension spring 35 is arranged in the tubular extension 16 for normally holding the valve 22 in a seated position 60 against the conical valve seat 14, and to further position the detent 24 in alignment with the lateral bore 20 whereby the spring pressed plunger 25 may cooperate therewith.

Also forming a part of the present invention is the U-shaped tube 36, one end there-

of being in communication with the gasoline trap depression 3, while the other end of said tube extends into the fitting 9 as shown very clearly in Figure 1. The purpose of this tube is to provide a means for trapping the gasoline 70 that does not enter the cylinders of the internal combustion engine and the gasoline that flows downwardly in the intake manifold will enter the pocket or trap 3, and will be delivered to the tube 36 from which the 75 trapped gasoline is delivered to the fitting, and the gasoline so entrapped will be returned with the fresh charge to the cylinders, thus preventing waste of the fuel and at the same 80 time permitting the trapped gasoline to be utilized as a primer to facilitate the easy starting of the engine.

In operation when the knob or handle 29 is grasped and the rod 28 is pulled rearwardly, the cable 32 will lift the spring plunger 25 85 upwardly out of engagement with the detent 24 and the suction will act on the blade-like element 23 and the valve 22 to draw the valve 22 outwardly away from the valve seat 14 so that the valve will assume the position 90 shown in Figure 3, and in this manner air will be permitted to enter through the passages 15 into the sleeve or shell 7 from which the air is delivered to the fitting 9 and in turn is discharged into the bore of the fitting 1 95 where the same becomes commingled with the incoming charge of fuel.

As the engine runs faster, the suction will naturally urge the valve 22 further away from the valve seat so that more air will be admitted, and therefore a properly mixed charge of air and gasoline will be delivered to the cylinders of the internal combustion engine. The U-shaped tube will prevent 100 waste of unburnt fuel, and in this manner the present invention will greatly increase the efficiency of the operation of the internal combustion engine as well as reduce the fuel consumption necessary to operate the engine. 105

A tube 37 extends from the fitting 9 and the outer end of this tube is normally closed by means of a cap 38 as shown very clearly 110 in Figure 3. This tube is to be used for removing carbon from the engine and in use the cap 38 is removed, and a rubber hose or the like is secured on the free end of the tube, the other end of the hose being connected with any suitable source of liquid that is to be 115 used in removing the carbon.

It will thus be seen from the foregoing description that I have provided a fuel economizer for use in conjunction with internal combustion engines which is of such construction as to permit the same to be readily and easily installed without necessitating any material alterations of the parts of the engine with which the device is associated, the 120 economizer being further positive and efficient in its operation at all times.

While I have shown the preferred embodi-

ment of my invention, it is to be understood that various changes in the size, shape and arrangement of parts may be resorted to without departing from the spirit of the invention and the scope of the appended claim.

Having thus described the invention, what I claim as new is:—

In a fuel economizer, an air valve unit comprising a body formed with a conical valve seat having air supply passages communicating with said seat and radiating therefrom, a valve stem slideable through the body, a conical valve on the inner end of the stem for the seat, resilient means for normally holding the valve in a closed position against the seat and over the passageway, and positive means for locking the valve on its seat against movement including a spring pressed plunger disposed laterally in the body, the valve stem being formed with a detent in which the lower end of the plunger rod is disposed when the valve stem is in one position, and manual means located at a remote point from the air valve for disengaging the plunger rod from the detent.

In testimony whereof I affix my signature.

RICHARD S. WALLENBERG.
